UNITED STATES PATENT OFFICE.

REUBEN B. BENJAMIN, OF CHICAGO, ILLINOIS, ASSIGNOR, BY MESNE ASSIGNMENTS, TO GENERAL ELECTRIC COMPANY, OF SCHENECTADY, NEW YORK, A CORPORATION OF NEW YORK.

LAMP-SUPPORTING DEVICE.

1,088,866.

Specification of Letters Patent.

Patented Mar. 3, 1914.

Application filed April 7, 1911. Serial No. 619,546.

To all whom it may concern:

Be it known that I, REUBEN B. BENJAMIN, a citizen of the United States, residing at Chicago, in the county of Cook and State of Illinois, have invented new and useful Improvements in Lamp-Supporting Devices, of which the following is a full, clear, concise, and exact description, reference being had to the accompanying drawing, forming a part 10 of this specification.

My invention pertains to electric lamp supporting devices; and especially relates to lamp sockets of a character adapted for series connection in high tension circuits.

15 It is the principal object of my invention to improve upon lamp supporting devices for series use in high tension circuits,—by rendering them simpler and more durable in construction, safer and more convenient 20 in use, and more economical to manufacture and maintain.

A high tension series socket, constructed in accordance with my invention, is described in the following specification and 25 shown in the accompanying drawings.

I have chosen the socket shown in the drawings as a good example of an embodiment of my invention, since it has been constructed and found entirely satisfactory; but 30 it is to be understood that the invention, as defined in the appended claims, may be embodied in other constructions.

In the drawings:—Figure 1 is an inverted plan of the body of the socket with the separable lamp receiver removed; Fig. 2 is a vertical section through the lamp socket, the section being taken on the line 2—2 of Fig. 1; Figs. 3 and 4 are fragmentary sectional views taken through the body of the socket 40 and the separable lamp receiver, the sections being taken on the lines 3—3 and 4—4, respectively of Fig. 1; Fig. 5 is a plan of the lamp receiver; Fig. 6 is a side elevation of the lamp receiver looking in the direction 45 opposite to the arrow (Fig. 5); Fig. 7 is a side elevation of the lamp receiver showing the side thereof opposite to that seen in Fig. 6; Fig. 8 is a horizontal section on the line 8—8 of Fig. 2 looking in the direction of the 50 arrows; and Fig. 9 is an inverted plan of the shade.

The socket shown in the drawings is made in two separable portions, one of which (herein termed the "body") is adapted to 55 be attached to a suitable supporting device,

such as a conduit or the like. The body carries the binding terminals and the center lamp engaging contact. The other portion (herein called the "lamp receiver") carries the threaded lamp receiving shell, which, 60 when the portions are connected together, is brought into electrical connection with one of the binding terminals. One of these portions carries a pair of contacts which, when connected, short-circuit the lamp engaging 65 contacts, and between which may be placed a film of mica, or other insulating material, of such thickness that it can be broken down by the current when the latter can find no shunt path through the lamp. By this 70 means the socket is short-circuited in case of the destruction of the lamp carried thereby and the extinguishing of the other lamps connected in the circuit is avoided.

Referring now to the drawings by reference characters, the body consists of a base 11 having two lateral knobs or extensions 12 formed integral therewith, around which knobs the conductors may be passed in order to lead them to the binding terminals. Secured to the base 11 by means of screws 13 is a supporting member 14, the upper end of which is threaded to receive a bushing 15 which is internally screw threaded to receive a conduit or other support 16. Surrounding the supporting member 14, and secured in place, through the agency of washers 17 and 18, by the bushing 15, is an insulating hood 19, the lower edge of which closely approaches the top surface of the base 11. 80 The hood 19 is of larger diameter than the base 11,—so that it will shed off rain water and aid in preventing the lamp carrying parts from becoming wet. The washer 18 is of rubber in order to prevent the admission of water into the space beneath the hood; and for the same reason a rubber disk 20 is inserted beneath the supporting member 14, the thickness of the disk 20, and the depth of the insulating hood 19, being such 85 that the lower edge of the hood presses firmly upon the rubber disk, whereby a watertight connection is formed.

The base 11 is hollowed out at its lower side to form a chamber 21 in which the various conducting parts of the socket are mounted. In a recess in the bottom of this chamber is secured, by means of a screw 22, a strip 23 which carries at one end a binding terminal 24, the strip being so arranged that 100 105 110

- the binding terminal 24 is located adjacent one end of a groove 25 formed in the lower face of the base directly beneath one of the knobs 12. As the knobs are formed integrally with the body, this arrangement insures that the line conductor shall not lie against any metallic member; and the insulation of the device is thereby increased. This groove provides a passage way for the lead conductor which is to be connected to the binding terminal 24. Clamped beneath the plate 23 is an arched resilient member which forms the center contact 26 of the socket. The contact 26 extends beneath a yoke-shaped lug 27 carried by a plate 28, and makes contact therewith, except when forced back by the end of a lamp. The plate 28 is clamped beneath a conducting strip 29, which is secured in place by means of screws 30. The strip 29 is provided with a binding terminal 31 disposed opposite to the binding terminal 24 and adjacent the end of a groove 32 similar to the groove 25. As has been stated, the resilient contact 26 is so arranged that, when a lamp is not in position in the socket, it will make connection with the lower side of the lug 27, electrical connection thereby being established between the binding terminals 24 and 31. The result is that the socket is short-circuited when a lamp is not in position in the socket, or when a lamp becomes so loose in the socket that it ceases to make contact with the center contact 26. The socket is intended to be connected in series with other sockets and, were this provision not made, the removal of one lamp would, in the absence of other safety devices, extinguish all the other lamps in the circuit.
- Extending across the bottom of the chamber 21 and connected at its center to the end of the plate 28 is a contact piece 33 the ends of which are bent up and over to form ears 34 and 35 by means of which the lamp receiver is secured to the base 11 and which serve to establish connection between the lamp receiving shell and the binding terminal 31 through the intermediary of the plate 28 and strip 29. A resilient tongue 36 is clamped between the strip 23 and the resilient contact 26, and is arranged to make connection with a corresponding contact on the lamp receiver for a purpose which will be hereinafter set forth. A leaf spring 37 is clamped between the plate 28 and the base and extends outward beside the yoke-shaped lug 27 and beyond the same. The spring 37 serves to lock the lamp receiver in connection with the body,—as will hereinafter be described.
- The lamp receiver comprises an insulating bushing 38 of such a size as to readily enter the chamber 21 of the body, and a threaded, lamp-receiving contact 39 mounted in the bushing 38 so as to be capable of longitudinal movement relatively thereto against the action of a spring. In order to effect this connection between the lamp-receiving sleeve 39 and the bushing 38, the former is flanged outwardly, as at 40, to provide a shoulder against which bears the lower end of a spring 41, the upper end of the spring bearing against an inwardly extending projection 42 with which the bushing 38 is formed. The upper end of the threaded contact 39 is provided with an outwardly extending flange 43, which engages against the top surface of the bushing 38, rotation between the threaded contact 39 and the bushing 38 being prevented by a downwardly turned lug 44 (Figs. 5 and 6), stamped out of the flange 43, which engages in a suitable recess in the bushing 38. It will be seen that this manner of connecting the threaded contact 39 with the bushing 38 permits the bushing to be moved longitudinally with relation to the threaded contact, against the action of the spring 41; however, the spring normally maintains the bushing in the position in which the flange 43 engages against the top surface of the bushing.
- In connecting the lamp receiver to the body, the ears 34 and 35 of the contact piece 33 of the latter enter beneath, and are maintained in position beneath, the flange 43 of the former, a bayonet connection between these parts being thus effected; and in order to obtain this result, the flange 43 of the lamp receiver is cut away at 45 and 46 to form notches through which may be passed the ears 34 and 35, respectively, of the contact piece 33. The top surface of the bushing 38 is cut away, adjacent the notches 45 and 46, to form recesses 47 and 48, into which the ears 34 and 35 enter when they are passed through the notches 45 and 46; so that, by effecting a turning movement of the lamp receiver relatively to the body, the ears 34 and 35 may be made to engage beneath the flange 43, just beyond the notches 45 and 46; by effecting a turning movement of the lamp receiver relatively to the body in an opposite direction the ears 34 and 35 are brought opposite the notches 45 and 46 of the flange 43, whereupon the lamp receiver may be withdrawn from the body. When the lamp receiver is connected to the body, as described above, current flows from the line to the binding terminal 24, and thence, via the center contact 26, to the center contact of the lamp (provided that a lamp is present in the socket), through the lamp to the threaded contact 39 and flange 43, and thence, through the contact piece 33 and plates 28 and 29, to the binding terminal 31 and the other line conductor. In case there is no lamp in the socket, the center contact 26 will spring outward into connection with the lug 27; and the socket will thereby be shorted.

circuited, the current flowing from the binding terminal 24, through the plate 23, to the center contact 26, and thence, through the lug 27 and plate 29, to the other binding terminal 31.

Lamp sockets of the character herein described are frequently used in situations where they are subject to considerable vibration; and it is desirable, therefore, to provide means for locking the lamp receiver in connection with the body, so that it cannot be accidentally separated therefrom, but may be removed by an attendant when it is desired to replace the dielectric or the like. To this end, I provide the insulating bushing 38 with a beveled surface 49 extending down one side thereof, and so located that it will be directly opposite to the leaf spring 37, referred to above, when the notches 45 and 46 of the flange 43 of the lamp receiver are brought opposite to the ears 34 and 35 of the contact piece 33,—preparatory to connecting the lamp receiver to the body. When, therefore, the lamp receiver is pushed inward relatively to the body, the leaf spring 37, of the body, engages the beveled surface 49; and is thereby sprung outward from its normal position. The bushing 38 is provided with a recess 50, which is located just beyond the beveled surface 49; so that a shoulder 51 is created between the recess 50 and the beveled surface 49. When the lamp receiver is turned, after being pushed forward to cause the ears 34 and 35 to enter the notches 45 and 46, to effect the bayonet connection of the lamp receiver with the body, the beveled surface 49 passes from behind the leaf spring 37; and the latter is enabled to snap into the recess 50. The leaf spring 37, thereafter, prevents backward rotation of the lamp receiver to effect the disconnection of the parts; this is owing to the engagement of the leaf spring 37 against the shoulder 51 (Fig. 8). Accidental separation of the lamp receiver from the body is thus prevented; but, when it is desired to disconnect the parts for some reason, this may be done by pulling upon the bushing 38, whereupon the latter moves outward relatively to the threaded lamp contact 39 and its flange 43, the latter parts remaining stationary relatively to the body. This outward movement of the bushing 38 has the effect of freeing the leaf spring 37 from the recess 50,—that is, moving the shoulder 51 out of the way of the leaf spring 37; and the bushing 38, carrying with it the lamp receiving contact 39, may then be turned until the notches 45 and 46 of the flange 43 come opposite the ears 34 and 35, the parts being thus disconnected. This disconnection of the parts occurs with a snap, owing to the tendency of the spring 41 (which is under tension) to return the threaded sleeve 39 to its normal position relatively to the bushing. This

snap action is very desirable in that it precludes any chance of sparking between the current carrying contacts.

A contact strip 52 is secured, at one end, to the flange 43 of the threaded lamp contact, the securing being effected by clamping the end of the strip beneath a pair of overturned lugs 53 formed upon the flange 43 (Figs. 5, 6 and 7), a suitable insulating filling being inserted between the strip 52 and the flange 43 and lugs 53,—whereby the contact strip is insulated from the flange 43. The contact strip 52 is adapted to make contact with a table 54 (Figs. 3 and 7), formed by stamping a portion of the flange 43 upward; it is prevented, however, from making such contact, under normal conditions, by a dielectric, which is inserted between the strip 52 and the table 54. The dielectric consists, in the construction shown, of a mica disk 55; but it may be of any of the well known forms. The contact strip 52 is so placed, upon the flange 43, that it will be engaged by the spring contact 36 referred to above, when the lamp receiver is connected with the body; so that a shunt path, broken only by the dielectric, is provided across the lamp terminals. When a lamp, in proper condition, is present in the socket, there is not enough difference of potential between the contact strip 52 and the table 54, to effect the breaking down of the dielectric: when, however, the lamp filament becomes burned out, or in case the lamp itself should be broken, the total voltage of the circuit occurs between the contact strip 52 and the table 54,—the result being that the dielectric is broken down, and current passes from the contact strip 52 to the table 54, the socket being thus short circuited. By this means, the extinguishing of the other lamps in the line is prevented. The defect may be remedied by removing the lamp receiver, inserting a fresh dielectric, and replacing the spoiled lamp by a new one.

The body is formed, at its lower face, with a circular channel 56 (Figs. 1 and 2) of such proportions as to conveniently receive the upper end of a shade 57, the shade being secured in position by means of screws 115 passing through an inwardly extending flange 58, with which the shade is provided, and entering suitable screw holes 59 in the body. A washer 60 is placed between the flange 58 and the body. In order that the lamp receiver may be connected with the body, it is necessary that the slots 45 and 46 be brought exactly opposite to the lugs 34 and 35, respectively; and, in order to facilitate this, the shade is provided with 120 a small notch 61 which forms a guide for a boss 62 which extends laterally from the insulating bushing 38 of the lamp receiver, the notch 61 and the boss 62 being so arranged that the slots 45 and 46 will be pre- 130

cisely opposite to the lugs 34 and 35 when the boss 62 is placed opposite to the notch 61. As the lamp receiver cannot be connected with the body without first passing the 5 boss 62 through the notch 61 of the shade, it will be seen that the correct relative positions of the lamp receiver and the body, prior to the connecting movement, is thus insured. In order to provide room for the 10 boss 62, when the latter is passed through the notch in the shade, and when it is turned when the bayonet connection is made, the body is formed with an elongated slot 63, located just behind the notch 61 of the shade 15 and extending beyond such notch in the direction in which the lamp receiver is rotated to effect the bayonet connection.

The lamp socket described above has several marked advantages over devices of a 20 similar character in the form in which it has hitherto been proposed to manufacture them. In the first place, there is very little danger of the dielectric becoming broken down, except in the case of the lamp filament burning out or becoming broken; for 25 instance, in case the lamp should jolt loose in the lamp receiver, or in case, for some reason, it should be desirable to remove the lamp without disconnecting the lamp receiver, the dielectric would not be broken down,—owing to the fact that a shunt path would be created across the center socket contact 26 and the lug 27 as soon as the lamp became sufficiently loose in the socket for 30 current to stop passing therethrough. In the second place, the separable parts of the socket are constructed so that they may be connected together with facility, and, when connected together, are locked so that 35 they cannot be separated except by a movement of a peculiar character—a movement which requires a conscious intention to effect it—being imparted to the lamp receiver; with the result that accidental separation 40 of the parts is practically impossible, while the parts may be separated, when desired, with the greatest ease. In the third place, the lamp receiver, when there is no lamp 45 therein, may be removed from the body without in any way affecting the electrical connections: this is an important advantage since it prevents sparking, which would otherwise be very liable to occur, owing to the high voltage of the line. Again, the 50 socket is of a simple construction, and there are no parts which are at all liable to get out of order in the course of the use of the device.

What I claim as new and desire to secure 60 by Letters Patent, is:

1. A separable lamp socket comprising a body, a center-lamp-terminal-engaging contact carried thereby, a second contact carried by said body, a lamp receiver detachably connected with said body and including an

outer-lamp-terminal-engaging contact having a portion making engaging connection with said second-named contact when the lamp receiver is connected with the body, and manually releasable means, actuatable from the outside of said lamp receiver, for connecting said lamp receiver with said body. 70

2. A separable lamp socket comprising a body; a center-lamp-terminal-engaging contact carried thereby; a second contact carried by said body, a lamp receiver adapted to be detachably connected with said body and including an outer-lamp-terminal-engaging contact adapted to make connection with said second-named contact when the lamp receiver is connected with the body; and means for connecting the lamp receiver with the body, said connecting means being detachable without removing the lamp from 80 said receiver. 85

3. A separable high-tension series socket comprising a body, including a support, a center-lamp-terminal-engaging contact carried by said support, and a second contact carried by said support; a lamp receiver including an outer-lamp-terminal-engaging contact adapted to make connection with the second-named contact of said body when the lamp receiver is connected to the body, and dielectric receiving contacts insulated from each other and adapted to make connection, one with said center-lamp-terminal-engaging contact, and the other with said outer-lamp-terminal-engaging contact, when said body and said lamp receiver are connected together. 95

4. A separable high-tension series socket comprising a body, including a support, a center-lamp-terminal-engaging contact carried by said support, a second contact carried by said support, and means for causing said center-lamp-terminal-engaging contact to make connection with said second-named contact when the lamp receiver is disconnected from said body; a lamp receiver including an outer-lamp-terminal-engaging contact adapted to make connection with the second-named contact of said body when the lamp receiver is connected to the body, and dielectric receiving contacts insulated from each other and adapted to make connection, one with said center-lamp-terminal-engaging contact, and the other with said outer-lamp-terminal-engaging contact, when said body and said lamp receiver are connected together. 100

5. A separable high-tension series socket comprising a body, including a support, a center-lamp-terminal-engaging contact carried by said support, a second contact carried by said support, and means for causing said center-lamp-terminal-engaging contact to make connection with said second-named contact when a lamp is not present in the 110 115 120 125 130

lamp receiver; a lamp receiver including an outer lamp-terminal-engaging contact adapted to make connection with the second-named contact of said body when the lamp receiver is connected to the body, and dielectric receiving contacts insulated from each other and adapted to make connection, one with said center-lamp-terminal-engaging contact, and the other with said outer-lamp-terminal-engaging contact, when said body and said lamp receiver are connected together.

6. A separable high-tension series socket, comprising a body, including a support, a contact carried by said support, a spring-center-lamp-terminal-engaging contact carried by said support, and adapted to make connection with said first-named contact when not engaged by the center terminal of a lamp; a lamp receiver including an outer-lamp-terminal-engaging contact adapted to make connection with the first-named contact of said body when the lamp receiver is connected to the body, and dielectric receiving contacts insulated from each other and adapted to make connection, one with said center-lamp-terminal-engaging contact, and the other with said outer-lamp-terminal-engaging contact, when said body and said lamp receiver are connected together.

7. A separable lamp socket comprising a body; a center-lamp-terminal-engaging contact carried by said body and adapted to be connected to a lead conductor; a metallic bayonet projection carried by said body and adapted to be connected with the other lead conductor; and a lamp receiver adapted to be detachably connected with said body, and having a bayonet slot for receiving said bayonet projection, said lamp receiver including an outer-lamp-terminal-engaging contact, and means for making connection between said outer-lamp-terminal-engaging contact and said bayonet projection when the lamp receiver is connected with said body.

8. A separable lamp socket comprising a body; a center-lamp-terminal-engaging contact carried by said body and adapted to be connected to a lead conductor; a metallic bayonet projection carried by said body and adapted to be connected with the other lead conductor; a lamp receiver adapted to be detachably connected with said body, and having a bayonet slot for receiving said bayonet projection, said lamp receiver including an outer-lamp-terminal-engaging contact, and means for making connection between said outer-lamp-terminal-engaging contact and said bayonet projection when the lamp receiver is connected with said body; and means for detachably locking said bayonet projection in the bayonet slot of the lamp receiver.

9. An electrical device comprising a body

member, a second member adapted to be detachably connected to said body member, a bushing movably secured to said second-named member, one of said members being provided with a bayonet projection and the other member being provided with a slot through which said projection may pass, whereby a bayonet connection may be established between the members, and means for locking said members in their connected condition, said locking means being releasable upon said bushing being moved relatively to said second-named member.

10. An electrical device comprising a member having a bayonet projection, a second member consisting of two relatively movable parts having a slot between them adapted to receive said bayonet projection, and means for locking said projection against withdrawal from said slot, said locking means being releasable upon one of said parts being moved relatively to the other.

11. A separable lamp socket comprising a body; a center-lamp-terminal-engaging contact carried by said body; a second contact carried by said body; a lamp receiver including an insulating member, and an outer-lamp-terminal-engaging contact connected to said insulating member so as to be movable relatively thereto, said outer-lamp-terminal-engaging contact being adapted to make connection with said second-named contact when the lamp receiver is connected with the body; said body and said lamp receiver being provided with inter-engaging bayonet projections and slots, whereby a bayonet connection may be established between them; and means for detachably locking the bayonet projection in the slots, said locking means being releasable upon said insulating member being moved relatively to said outer-lamp-terminal-engaging contact.

12. A separable lamp socket comprising a body; a center-lamp-terminal-engaging contact carried by said body; a second contact carried by said body; a lamp receiver including an insulating member, and an outer-lamp-terminal-engaging contact connected to said insulating member so as to be movable relatively thereto, said outer-lamp-terminal-engaging contact being adapted to make connection with said second-named contact when the lamp receiver is connected with the body; said body and said lamp receiver being provided with inter-engaging bayonet projections and slots, whereby a bayonet connection may be established between them; and said body and said lamp receiver being formed with a supplemental projection and slot for insuring the correct positioning of the lamp receiver when connecting it to the body.

13. A separable lamp socket comprising a body; a center-lamp-terminal-engaging contact carried by said body; a second contact

- carried by said body; a lamp receiver including an insulating member having a lateral projection, and an outer-lamp-terminal-engaging contact connected to said insulating member so as to be movable relatively thereto, said outer-lamp-terminal-engaging contact being adapted to make connection with said second-named contact when the lamp receiver is connected with the body; 5 said body and said lamp receiver being provided with inter-engaging bayonet projections and slots, whereby a bayonet connection may be established between them; and a shade carried by said body and having a slot therein for guiding the lateral projection of said lamp receiver when the parts are connected together.
14. An electrical device comprising a body member, a second member adapted to be 10 detachably connected to said body member, a bushing secured to said second-named member so as to be longitudinally movable relatively thereto, one of said members being provided with a bayonet projection and the other member being provided with a slot through which said projection may pass, whereby a bayonet connection may be established between the members, said first-named member and said bushing being provided, 15 one with a recess, and the other with a resilient member adapted to spring into said recess when the members are connected together, whereby said members are locked together in such manner as to be releasable when said bushing is moved longitudinally relatively to said second-named member.
15. A separable lamp socket comprising a body; a center-lamp-terminal-engaging contact carried by said body; a second contact carried by said body; a lamp receiver including an insulating member, and an outer-lamp-terminal-engaging contact connected to said insulating member so as to be longitudinally movable relatively thereto, 20 said outer-lamp-terminal-engaging contact being adapted to make connection with said second-named contact when the lamp receiver is connected with the body; said body and said lamp receiver being provided with inter-engaging bayonet projections and slots, whereby a bayonet connection may be established between them; said body and the insulating member of said lamp receiver being provided, one with a recess, and the other with a resilient member adapted to spring into said recess when the lamp receiver is connected with the body, whereby the lamp receiver is locked to the body in such manner as to be releasable when the insulating member is moved longitudinally relatively to the outer-lamp-terminal-engaging contact.
16. A high tension series socket comprising two separable portions, a center lamp terminal engaging contact carried by one of said portions, an outer lamp terminal engag- 25
- ing contact carried by the other portion, and a pair of contacts carried by one of said portions and adapted to receive a film resistance between them.
17. A high tension series socket comprising a body, a center lamp terminal engaging contact carried by said body, a lamp receiver separably connected with said body, an outer lamp terminal engaging contact carried by said lamp receiver, and a pair of contacts carried by said lamp receiver, said contacts being adapted to receive a film resistance between them. 30
18. A high tension series socket comprising a body, binding terminals on said body, a center lamp terminal engaging contact mounted on said body and electrically connected to one of said binding terminals, a connecting member carried by said body and electrically connected with the other binding terminal, and a lamp receiver removably connected to said body, said lamp receiver comprising an insulating member, an outer lamp terminal engaging contact carried by said insulating member and adapted to make connection with said connecting member when the lamp receiver is connected to said body, and a pair of contacts adapted to receive a film resistance between them. 35
19. A high tension series socket comprising a body, binding terminals carried by said body, a spring center contact carried by said body and connected with one of said binding terminals, means connected with the other binding terminal and adapted to be engaged by said center contact when a lamp is not present in the socket, and a lamp receiver separably connected with said body, and comprising an insulating member, an outer lamp terminal engaging contact adapted to make connection with the binding terminal other than that to which said center lamp contact is connected, and a pair of contacts adapted to receive a resistance film between them. 40
20. A high tension series socket comprising two separable portions, one of said portions carrying binding terminals and a lamp terminal engaging contact connected with one of said binding terminals, and the other of said portions carrying a second lamp terminal-engaging contact and a resistance film supporting member arranged to cooperate with said lamp terminal engaging contact when the portions are connected together. 45
21. A high tension series socket comprising a body having binding terminals thereon, a center lamp terminal engaging contact mounted on said body and electrically connected with one of said binding terminals, a second contact electrically connected with said first-named contact, a connecting member carried by said body and electrically connected to the other binding terminal, and a lamp receiver adapted to be removably connected 50

nected to said body, said lamp receiver comprising an insulating member, an outer lamp terminal engaging contact carried by said insulating member and adapted to make connection with said connecting member when the lamp receiver is connected to said body, and a resistance film supporting device electrically connected with said outer lamp engaging contact adapted to coöperate with said second-named contact when the lamp receiver and the body are connected.

22. An electrical device comprising a member having a bayonet projection, a second member consisting of two relatively

movable parts having a slot between them 15 adapted to receive said bayonet projection, and means for locking said projection against withdrawal from said slot, said locking means being releasable upon one of said parts being moved relatively to the other. 20

In witness whereof, I have hereunto subscribed my name in the presence of two witnesses.

REUBEN B. BENJAMIN.
